(57) **CLAIM**

The ornamental design for a channel reveal with ribbed flanges, as shown and described.

DESCRIPTION

FIG. 1 is a top perspective view of a channel reveal with ribbed flanges, showing our new design;

FIG. 2 is a bottom perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in FIGS. 1–8 are included for purposes of illustrating portions of the channel reveal with ribbed flanges that form no part of the claimed design. The channel reveal with ribbed flanges is shown with a symbolic break in its length. The appearance of any portion of the channel reveal with ribbed flanges between the jagged break lines forms no part of the claimed design.
